UNITED STATES PATENT OFFICE.

GEORGE RAYMOND, OF CHICAGO, AND JOHN H. FINLAY, OF WARSAW,
ILLINOIS.

PULVERIZER.

No. 812,231.

Specification of Letters Patent.

Patented Feb. 13, 1906.

Application filed July 26, 1902. Renewed May 31, 1905. Serial No. 263,162.

To all whom it may concern:

Be it known that we, **GEORGE RAYMOND**, residing at Chicago, in the county of Cook, and **JOHN H. FINLAY**, residing at Warsaw, in the county of Hancock, State of Illinois, citizens of the United States, have invented a certain new and useful Improvement in Pulverizers, (Case No. 2,) of which the following is a full, clear, concise, and exact description, reference being had to the accompanying drawings, forming a part of this specification.

Our invention relates to pulverizers or crushing machinery, and particularly to that class of pulverizing machinery which employs the principle of gravity in conjunction with other forces to effect the desired impact upon the material to be pulverized or crushed.

In general the object of our invention is to provide a machine of improved simplicity of construction and ease of operation, whereby the general efficiency thereof may be improved.

In accordance with our invention we provide a rotating shaft, upon which are mounted one or more sections of a drum, near the periphery of which there are pockets adapted to contain the material to be pulverized and suitable weights for effecting the impact which is to pulverize said material. We further provide a casing for said drum in which there are openings, through which openings the material to be operated upon may pass. The pockets and openings are preferably so formed and placed that the material will pass through the openings due to the attraction of gravity when the said pockets reach the lower position of their rotation. A screen is provided which surrounds the casing and rotates therewith and through which the material passes when it has reached the desired degree of pulverization. The material which does not pass through the screen is carried around with the same to an upper point in the revolution of the drum, where it re-enters the pockets through the openings in the casing, where it may be again acted upon by the impact of the weights within the pockets. It is desirable to further provide some means of feeding material into the machine and to further provide an inclosing housing to prevent the escape of dust and to catch the pulverized material dropping through the screen.

Our invention will be best understood by

reference to the accompanying drawings, in which—

Figure 1 is a front elevation, parts being broken away to show the interior mechanism. Fig. 2 is a vertical longitudinal section taken on line 2 2 of Fig. 3, and Fig. 3 is a cross-sectional view taken on line 3 3 of Fig. 2.

Like parts are indicated by similar characters of reference throughout the different figures.

We have shown a main shaft 1, driven by the gear 2 and its associated pinion 3, which is connected, by means of the counter-shaft 4, with the pulley 5, these shafts being supported in bearings 6 6. Upon the shaft 1 are keyed the hub-sections 7 7, which carry the sections 8 8 of the rotating drum. Any desired number of these sections may be mounted upon the shaft. In Fig. 1 we have shown a mill in which there are four such sections, while in the other two figures there are but two such sections shown. These sections are securely fastened to the hub, preferably by means of the wooden wedges 9 9. When there is more than one section mounted upon the same shaft, it is desirable that the sections should be displaced angularly about the shaft 1, so that the impact due to the falling weights will not occur in unison, as will be hereinafter more fully understood. Near the periphery of the sections 8, forming the drum, are provided irregularly-shaped pockets 10 10. In the present form of our invention we have shown spherical balls 11 11, adapted to tumble in said pockets. It will, however, be understood that any form or shape of weight may replace the said balls. When balls are used as the tumblers, we find it desirable to provide a central ridge 12 in each of the pockets. The pockets in each section of the drum are further provided with end walls 13 13, which, together with the central ridges 12, form raceways in the pockets, one for each ball, which serve to guide and partially control the rolling and tumbling motion thereof.

A desirable cross-sectional shape for the pockets is best illustrated in Fig. 3, and the rotation of the drum being in the direction shown by the arrow 14 the movement of the balls within their pockets is well illustrated in said figure. Upon the right-hand side where the ball is being elevated due to the

power supplied to the mill it will be seen that the ball rolls down the incline 15 to a position in the socket 16 near the axis of rotation. The ball is held within this socket 16 until it reaches a point slightly beyond the highest point in its rotation. The ball then rolls out of its elevating-socket and rolls or drops to the mortar portion 17 of the pocket. Upon reaching the lower part of the revolution the ball rolls from the mortar, and it is then carried by the casing 18 until it again rolls into the elevating-socket. This casing 18 is preferably made of boiler-plate and forms a shell tightly fitting about the entire rotating drum and rotating therewith. This casing 18 is provided with openings 19 19, communicating with the interior of the pockets 10, and is further provided with projecting scoops 20 20, which, as will be hereinafter more fully explained, are adapted to direct material through the openings into the pockets. End plates 21 21 are bolted to the end sections of the drum and are provided with flanges 22 22, to which is secured the cylindrical screen 23. We find it desirable to make the said screen in sections, as best illustrated in Fig. 3, these sections being fastened to connecting-bars 24, the various sections being held together by the bolts 25. One or both of the end plates 21 are desirably dished and provided with an opening 26, through which material may be charged. In the present embodiment of our invention we have shown a hopper 27, having a circular rim 28, which fits within the opening 26 of the end plate. A housing 29, preferably of sheet metal, incloses the mill, as shown:

The operation of our improved mill will now become apparent. The material to be pulverized is charged into the hopper 27 and passes through the opening in the end plate and thence through the openings 30 30 in the end walls of the pockets 10 10. The drum with its inclosing casing and screen rotating in the direction shown by the arrow 14, it will be seen that the material enters the pockets when they are at a lower point in their revolution; but at this point it will at once drop through the openings 19 19 upon the screen 23, where it will be carried upward upon the right-hand side. As the material approaches the upper point in the revolution of the screen it will drop from the screen to the casing and thence through the openings 19 into the pockets 10 and covering the balls 11. The scoops 20 20 are designed to assist in directing the material carried upward by the screen to the openings in the casing. As the pocket passes over the upper center the material will drop to the mortar 17, where it at once becomes subject to the impact of the falling ball discharged from the pocket 16. Upon approaching the lower point in its revolution the material is again discharged through the openings in the inclosing casing

to a position upon the screen 23, when the cycle of operations is again repeated. When the material or any of it becomes sufficiently pulverized, it drops through the meshes of the screen and is caught within the housing, from which it may be removed in any suitable manner. It will be seen that the openings 30 in the end walls of the various sections come into partial register, as shown in Fig. 3, thus serving to permit the passage of the material from the end section to those sections near the middle of the machine; but this longitudinal distribution of the material is also effectively brought about by its alternate discharge upon the screen 23 and readmission to the pockets 10.

It will be apparent that our machine combines all the advantages of the tumbling-barrel principle of pulverization with many advantages not heretofore incorporated in pulverizing-mills. We find that a mill of our improved construction will pulverize a given quantity of material in a comparatively short space of time and with a comparatively small supply of power, for the reason that the tumblers are elevated to their uppermost position while relatively near the axis of rotation, thereby requiring a proportionately small turning moment, the turning moment required to elevate the said tumblers being very largely supplied by the moment caused by the impact of the falling tumblers upon the mortar, which is placed near the periphery of the drum. Furthermore, by the use of the pockets in the drum and the openings in the inclosing casing the material to be pulverized is effectively separated from the tumblers at all points of the revolution except that at which the said material is advantageously acted upon by the tumblers. There is a further advantage in that a comparatively small quantity of material is necessary to be carried in the drum of the mill in order to advantageously utilize the full force of the impact of the falling tumblers, nearly all of the material carried by the drum being acted upon during each revolution.

While we have herein shown and particularly described one embodiment of our invention, it will be apparent that our invention may be advantageously applied to other constructions, and we do not, therefore, wish to limit ourselves to the precise disclosure herein set forth; but,

Having described our invention, we claim as new and desire to secure by Letters Patent—

1. In a pulverizing-mill, the combination with a rotating drum having pockets, of peripheral openings in said pockets, peripheral scoops adapted to guide material to said openings, tumblers confined within said pockets, and a screen surrounding said drum and rotating therewith, substantially as described.

2. In a pulverizing-mill, the combination

with a rotating drum, of pockets in said drum, peripheral openings in said pockets, tumbler-balls confined within said pockets, said pockets being provided with inclines 15 and sockets 16, whereby said balls are carried in said sockets during the upward part of their revolution and with raceways to guide the motion of said tumblers, and a cylindrical screen surrounding said drum and rotating therewith, substantially as described.

3. In a pulverizing-mill, the combination with a rotating drum, of pockets in said drum, peripheral openings in said pockets, tumbler-balls confined within said pockets, said pockets being provided with inclines 15 and sockets 16, whereby said balls are carried in said pockets during the upward part of their revolution and with raceways to guide the motion of said tumblers, a cylindrical screen surrounding said drum and rotating therewith, and scoops adapted to guide material to said openings, substantially as described.

4. In a pulverizing-mill, the combination with hub portions 7 of similar drum-sections 8, provided with pockets 10, said drum-sections being displaced angularly, and tumblers confined within said pockets, substantially as described.

5. In a pulverizing-mill, the combination with hub portions 7 of similar drum-sections 8, provided with pockets 10, said drum-sections being displaced angularly, wooden wedges whereby said drum-sections are keyed to said hub portions, and tumblers confined within said pockets, substantially as described.

In witness whereof we hereunto subscribe our names this 24th day of July, A. D. 1902.

GEORGE RAYMOND.
